CLAIM

The ornamental design for a dial switch for vehicle, as shown and described.

DESCRIPTION

FIG. 1 is a front perspective view of a dial switch for vehicle showing a first embodiment of our new design;

FIG. 2 is another front perspective view thereof;

FIG. 3 is a front view thereof;

FIG. 4 is a left side view thereof;

FIG. 5 is a right side view thereof;

FIG. 6 is a top view thereof;

FIG. 7 is a bottom view thereof;

FIG. 8 is a front perspective view of a dial switch for vehicle showing a second embodiment of our new design;

FIG. 9 is another front perspective view thereof;

FIG. 10 is a front view thereof;

FIG. 11 is a left side view thereof;

FIG. 12 is a right side view thereof;

FIG. 13 is a top view thereof; and,

FIG. 14 is a bottom view thereof.

The appearance of the gradation in the respective views indicates the shape, texture, and contour of the invention surface.
